Primary Examiner — Marissa J Cash(74) *Attorney, Agent, or Firm* — Wayne & Ken, LLC; Tony Hom(57) **CLAIM**

A new, original, ornamental design for a drone, as shown and described.

DESCRIPTION

FIG. 1 is a perspective view of a drone showing my new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines in the figures illustrate portions of the drone that form no part of the claimed design.
